W. H. GODWIN

COLLAR BUTTON

Filed May 4, 1921

Fig. 4.

Inventor
W.H. Godwin,

By *Elmer Talbert*

Attorney

UNITED STATES PATENT OFFICE.

WILLIAM H. GODWIN, OF SUMNER, WASHINGTON.

COLLAR BUTTON.

Application filed May 4, 1921. Serial No. 466,678.

To all whom it may concern:

Be it known that WILLIAM H. GODWIN, a citizen of the United States of America, residing at Sumner, in the county of Pierce 5 and State of Washington, has invented new and useful Improvements in Collar Buttons, of which the following is a specification.

The purpose of the invention is to provide a simple and inexpensive device of the kind 10 mentioned to be made from sheet material and of such a form that it may function properly irrespective of the position in which it is inserted in the shirt band. A further purpose is to construct a button of 15 the kind mentioned so that it may have an alternative use as a garment supporter particularly for waist-line garments.

The invention is illustrated and described in a specific embodiment to which, however, 20 it is not to be restricted. The right is reserved to make such changes or alterations as the actual reduction to practice may suggest, in so far as such changes or alterations are compatible in spirit with the annexed 25 claim.

In the accompanying drawings:

Figure 1 is a perspective view of the neck 30 portion of a shirt and its attached collar, the invention being shown as the attaching means between the shirt neck band and the collar.

Figure 2 is a perspective view showing the 35 button as constructed for use in the front of the shirt.

Figure 3 is a perspective view showing the 40 invention as used in the rear of the shirt neck band.

Figure 4 is a vertical sectional view 45 through Figure 1 at the front of the collar.

Figure 5 is a similar view through the 50 structure of Figure 1 at the back of the collar.

The button is made of sheet material comprising the body portion 1 from which the 55 tongue 2 is struck, the latter being bent at right angles to the body portion and then bent back in substantial parallelism to the body portion to provide a bill 3. In the collar button used in the front of the shirt, that portion of the tongue comprehended between the bill and the body portion is of sufficient length to accommodate the three thicknesses or plies that it must carry by reason of its use in the front, the bill 3 bent 60 back toward the body portion 1 and the ter-

65 minal 4 constitutes a foot for bearing engagement with the outer tab of the collar and serves by reason of the resilience of the material of which the device is made to hold the two tabs of the collar against each other and the inner tab back against the 70 collar band. The body portion 1 is of such width when the tongue 2 is upstruck there are left the two ears 5 constituting bearing feet which lie in the same plane as the body 75 portion and bear against the collar band on the opposite sides of the button hole from the body portion 1.

The button shown in Figure 3 is substantially the same as that shown in Figure 2, 80 having a body portion 1^a, the ears 5^a, and the tongue 2^a of which the bill 3^a instead of being of the shape shown in Figure 2 is flat and is disposed in parallelism with the body portion 1^a, the space between the 85 bill 3^a and the body portion 1^a being sufficient to accommodate the thickness of the neck band and the inner ply of the collar.

The button shown in Figure 2 is formed preferably with a hole 6 in the body portion 90 to serve as a means for attaching it to a part of the garment if it is desired at any time to use the device as a support for waist line garments.

Having described the invention, what is 95 claimed as new and useful is:—

A collar button consisting of a blank of sheet material having a substantially flat body portion and an integral tongue rising from the plane of the body portion substantially midway of the length thereof and deflected in the form of a bill which lies in substantial parallelism with the plane of the body portion, the tongue being of a width less than the body portion and being 100 separated at its side edges therefrom by slits forming side ears which extend in the plane of the body portion and in the opposite direction from the tongue, the ears being of a length approximating that portion of 105 the body which is overhung by the tongue to prevent tilting of the button when in use, the said bill being concaved longitudinally and having its free end portion projecting beyond the opposite transverse edge of the 110 body.

In testimony whereof he affixes his signature.

WILLIAM H. GODWIN.
